UNITED STATES PATENT OFFICE

142,404

DESIGN FOR A WRIST WATCH STRAP

Alexander Greenberg, New York, N. Y.

Application April 27, 1945, Serial No. 119,251

Term of patent 7 years

(Cl. D45—4)

To all whom it may concern:

Be it known that I, Alexander Greenberg, a citizen of the United States, residing at 325 Lafayette Street, in the county and State of New York, have invented a new, original, and ornamental Design for Wrist Watch Straps, of which the following is a specification, reference being had to the accompanying drawing, forming part thereof.

I claim:

The ornamental design for a wrist watch strap, as shown.

ALEXANDER GREENBERG.
